HAND PRINTER

Filed July 10, 1933

UNITED STATES PATENT OFFICE

1,984,645

HAND PRINTER

Rush Jordan, Dillon, Mont.

Application July 10, 1933, Serial No. 679,683

4 Claims. (Cl. 101—333)

This invention relates to hand printers and has as one of its objects to provide a hand printer that is self contained.

Another object of the invention is to provide a hand printer having movable and interchangeable type fonts.

A further object of the invention is to provide a hand printer that will utilize the weight of the type font to act as a securing means for the paper to be printed.

A further object of the invention is to provide a hand printer having self aligning printing elements.

With these and other objects in view reference is now had to the accompanying drawing in which

Fig. 1 is a perspective view of the printer complete;

Fig. 2 is an end elevation thereof with part of the type tray broken away;

Fig. 3 is a similar view to Fig. 2 showing the paper holder and tray raised;

Fig. 4 is a plan view of a fragment of the font;

Fig. 5 is an end view of a cleat; and

Fig. 6 is a perspective view of one of the printing arms.

Having reference to the drawing like numerals refer to like parts throughout the several views and the numeral 1 refers to the invention as a whole which consists in general of a base 2 whose upper surface is finished to provide a platen 3, and a travelling font 4.

The base 2 is constructed of any substantial material that will provide a firm platen upon which a card or paper (not shown) to be printed may rest evenly to receive a perfect impression.

While no mention of the material to be printed upon is made in the claims it is obvious that a sheet of such material for the purpose is necessary, however an impression against the platen 30 is beyond dispute the equivalent of an impression against the material intended to carry the printed matter and must be so understood.

Upon the platen 3 is provided, preferably at its rear edge 5, a raised portion which may consist 45 of blocks 6 as shown, or other means of providing an elevation, for a purpose to be explained, and a gauge 7 as shown in Fig. 1, may also be provided thereon for a purpose to be explained.

Legs or buttons 8 serve as supports for the printer in the usual manner.

A track is now provided on the printer and is disposed in parallel relation to the desired printing line 9 and consists of a guide rail 10 formed 55 in the manner shown in Figs. 1, 2 and 3, with its

lower edge folded to provide a slot 11 as shown, and also a work rail 12.

The guide rail 10 is rigidly attached to the blocks 6 whereby it assumes a position elevated above the platen 3, and the work rail 12 is hingedly attached to the blocks, as at 13, in a manner to assume a position at an elevation below that of the guide rail, and is hingedly attached for movement in a vertical arc.

Attached to the work rail 12 is a space bar 14 10 consisting of a straight plate notched for a purpose to be explained, and the bar is extended above the rail to provide a stop 15, and this bar obviously raises with the work rail 12.

Mounted on and engaging the track is the self 15 inking type font 4 which consists of a tray 16 having one side 17 open and disposed to rest on the work rail 12 and positioned adjacent the space bar 14, and its opposite side 18 is provided with a back 19 that extends downward below the 20 bottom 20 of the tray 16 there terminating in a tongue 21 which removably, rockably and slidably engages the guide rail 10 by passing through the said slot 11 formed therein for the purpose, by which means movement of the tray will be held in 25 aligned relation with the platen 3 and guidedly parallel with the printing line 9.

The difference of elevation of the rails, and the tray resting thereon, places the tray at an angle with respect to the platen and this position of 30 the tray is termed the observation angle as it presents the contents of the tray more clearly to the view of the operator.

The tray 16 is now positioned with respect to the work rail 12 that it may be raised in a vertical arc 35 therewith, as shown in Fig. 3, a space being left between its front edge (or open side 17) and the space bar 14 to accommodate movement on the different hinge points of the tray and the work rail.

It is now evident that the tray 16 is secured to the guide rail 10 by its tongue 21; that it will readily slide on said guide rail; that it will rock on the guide rail during the raising and lowering thereof; and that it is removable therefrom by 40 sliding the tongue endwise and off the guide rail.

This latter arrangement now permits the use of interchangeable trays as, for instance, trays containing different type faces may be substituted 45 for one another where it is desired to bring out or emphasize some statement more emphatically.

The tray 16 is further provided with cleats 22, formed in rows in the bottom 20 thereof in any suitable manner, or the cleats may consist of a 50 55

piece of metal 23 preferably U shaped in cross section, as shown in Fig. 5, for a purpose to be explained, and when in the form of a U the pair of side arms 24 will form the cleats while the bottom part 25 of the U will provide for securement to the bottom 20 of the tray by soldering, spot welding, or the like, and an ink pad 26 of the usual type is mounted between the side arms 24 of the cleats for contact with printing members 10 27 when in the normal position in the font.

The font 4 is now completed by the addition of said printing members 27 which consist of any type suitable for the purpose but preferably of the rubber stamp variety having a rubber type face 15 (not shown) attached to the block 28, the block being shaped to grip conveniently thus providing a handle portion.

The block 28 in this case has the exposed surface of the handle portion flattened and indicating 20 characters are placed thereon, as at 29, whereby when the printing members are placed uniformly in their normal position in the tray, as in rows corresponding with the cleats, and at the observation angle of the font, a convenient and very plainly 25 visible key board is provided, as by the observation angle the type members 27 are superimposed one above the other, and in a bank, and are thus decidedly accessible and visible.

As shown in Fig. 4 two widths of blocks 28 may 30 be utilized to conserve space by reducing the size of the font thereby reducing the overall length of the printer, and this may be done by grouping the punctuation marks and the narrower letters and numbers in a bank by themselves.

The printing members 27 are made an integral 35 part of the tray 16 by being hingedly attached thereto by means of the said cleats, and by arms 30 properly distributed and of predetermined lengths connecting the members therewith, and these arms are disposed to permit withdrawal of the members of the tray in a circular path over preceding members (illustrated by the curved lines in Fig. 2) so that any member in a row may be 40 optionally directed to the printing line without interference from the remaining members.

As a single arm is provided for each printing member the ends of the arms are enlarged, as at 31, to provide a substantial bearing at the point of connection with both the block 28 and the side arms 24 whereby the type face will be caused to evenly impress the paper, and they are offset, as at 32, and operate from alternate sides of the cleats to prevent interference during operation.

It is now apparent that with the tray secured 55 against disalignment by the guide rail, and with the type members integral therewith, that impressions made against the platen will be automatically aligned with the platen and obviously with the printing line.

The arms 30 in their movement to make the impression must engage one of the notches of the space bar 14 and the notches of the space bar are spaced to provide uniform and automatic spacing 60 between the characters during operation.

While the printing members are integral with the tray the use of interchangeable false bottoms carrying the printing members and attachable to the tray is considered an equivalent.

In use the desired font is mounted on the guide rail with its front resting on the work rail.

The work rail is now raised in a vertical arc away from the platen which also raises the font when the card to be printed may be positioned 75 against the gauge in proper register for print-

ing there to be secured in position by lowering the work rail thereon.

It will be noted by reference to the drawing that the work rail is made relatively heavy; that the space bar secured thereto makes for additional weight; and that the type font resting thereon will increase the weight until combinedly there is provided sufficient weight to substantially hold the paper permanently in place for printing.

With the paper now in proper register and secured the first letter of the sentence is drawn from the font, the font being moved to proper position in the line at the same time and by the type member (or may be assisted by the operator's other hand), when the impression is made by dropping the arm into the proper notch of the space bar and contacting the paper with the inked type face.

The type member is now replaced in the font 20 and a second member for the sentence utilized in like manner and repeated until the sentence is completed and the printing finished, when all type members will have been returned to place and no after-work remains except that of with- 25 drawing the card from the printer.

Withdrawing the card requires a similar movement of the work rail and it will be noted that the side arms 33 of this member 12 projects beyond the platen to form a finger-hold for the 30 purpose of raising, but, it is obvious that a button or handle means (not shown) may be attached to this rail for the purpose if desired.

Having thus described my invention I claim:

1. A hand printer comprising a platen, a track 35 mounted on said platen in parallel relation to the desired printing line, a type font removably and slidably mounted on said track and consisting of a tray, a tongue attached to said tray for engagement with said track, cleats provided in 40 the bottom of said tray, printing members having exposed indicating characters, providing a key board, arms pivotally connecting said members and said cleats and arranged to direct said members in a circular path from said tray to the 45 printing line, guided by said track.

2. A hand printer comprising a platen, a track mounted on and above said platen and in parallel relation to the desired printing line, a self inking type font consisting of a tray removably 50 and slidably mounted on said track, pairs of cleats provided in the bottom of said tray, an ink pad disposed between each pair of cleats, printing members normally resting in a bank, and in rows on said pads and forming a key 55 board, arms pivotally connecting said printing members and said cleats, and arranged with said cleats to optionally direct any member in a row to the printing line over preceding members to impress against the platen.

3. A hand printer comprising a platen, a track mounted on said platen in parallel relation to the desired printing line, said track consisting of a guide rail rigidly attached to and positioned at an elevation above said platen, and a work rail hingedly attached to said platen at an elevation below said guide rail, a self inking type font removably and slidably mounted on said track and arranged thereon to provide an ob- 65 servation angle thereto by the respective elevations of said rails, said font consisting of a tray, cleats, in rows, formed in said tray, printing members normally superimposed one above the other in rows and provided with indicating char- 70

acters to form a key board, arms pivotally connecting said printing members and said cleats, and arranged to optionally direct any member in a row to the printing line, and in a circular 5 path over preceding members, to impress against said platen.

4. A hand printer comprising a platen, a pair of elevating blocks attached to said platen, a track mounted on said platen in parallel relation 10 to the desired printing line, said track consisting of a guide rail rigidly attached to said blocks and a work rail hingedly attached to said blocks and disposed at a lesser elevation than said guide rail, and movable in a vertical arc, a space bar 15 attached to said work rail, a self inking type

font removably, rockably and slidably mounted on said track and arranged thereon to provide an observation angle thereto by the respective elevation of said rails, and rockable in a vertical arc with said work rail, and forming with said work rail, said space bar and said font a substantial securing weight, printing members hingedly attached to said font by arms and providing a key board, said arms being registerable with the spaces of said space bar to automatically space the printed letters, and to optionally direct any member to the printing line in a circular path and over preceding members to impress against said platen. 5
